US00D605206S

(12) **United States Design Patent**
Yabe et al.

(10) **Patent No.:** **US D605,206 S**
(45) **Date of Patent:** **** Dec. 1, 2009**

(54) **FAN SHROUD FOR CONSTRUCTION MACHINERY**

(75) Inventors: **Mitsuo Yabe**, Hiratsuka (JP); **Masahiro Ikeda**, Chigasaki (JP); **Tomoya Watanabe**, Hiratsuka (JP)

(73) Assignee: **Komatsu Ltd.**, Tokyo (JP)

(**) Term: **14 Years**

(21) Appl. No.: **29/327,473**

(22) Filed: **Nov. 6, 2008**

(30) **Foreign Application Priority Data**

May 7, 2008 (JP) 2008-011484

(51) **LOC (9) Cl.** **15-03**

(52) **U.S. Cl.** **D15/28; D23/411**

(58) **Field of Classification Search** ..... **D15/5, D15/10, 17, 28, 31, 144, 199; D23/411, D23/412, 414, 386, 324, 381, 382; D12/196, D12/197, 216; D24/232; 415/173.1, 215.1, 415/213.1, 126, 127, 214.1, 223; 416/244 R, 416/247 R; 180/68.6, 68.4; 123/41, 49, 123/41.7; 165/122**

See application file for complete search history.

(57) **CLAIM**

The ornamental design for a fan shroud for construction machinery, as shown and described.

DESCRIPTION

FIG. 1 is a perspective view of a fan shroud for construction machinery showing our new design;

FIG. 2 is a front view thereof;

FIG. 3 is a rear view thereof;

FIG. 4 is an enlarged top plan view thereof, the opposite side view being a mirror image thereof;

FIG. 5 is an enlarged right side view thereof, the opposite side view being a mirror image thereof; and,

FIG. 6 is an enlarged cross-sectional view taken along line 6—6 in FIG. 2.
